UNITED STATES PATENT OFFICE.

FRANK H. STANWOOD, OF CHICAGO, ILLINOIS, ASSIGNOR TO STANWOOD EQUIPMENT COMPANY, OF BOSTON, MASSACHUSETTS, A CORPORATION OF MAINE.

HAND-PAD.

1,259,798.

Specification of Letters Patent. Patented Mar. 19, 1918.

Application filed July 19, 1917. Serial No. 181,455.

To all whom it may concern:

Be it known, that I, FRANK H. STANWOOD, a citizen of the United States, residing in Chicago, in the county of Cook and State of Illinois, have invented a new and useful Improvement in Hand-Pads, of which the following is a specification.

This invention relates in general to hand pads for automobile doors and the like.

10 A principal object of the present invention is the provision of a pad which will conform accurately to the shape of the door, over which it depends, under pressure of the hand.

15 A further object of the invention is the provision of a hand pad having a leather exterior and resembling those already in use, which will lie permanently against the outer surface of the car and not possess a tendency to curl at the edges as do the other ones generally in use prior to my invention.

20 A further and highly important object of the invention is the provision of a hand pad which under normal conditions will lie close against the side of the door and which upon being bent back and away therefrom will not return to normal position until it is again pressed against the door. This permits the easy cleaning of the door behind the 25 pad and the redecorating of the car without removing the hand pad.

25 A still further object of the invention is the provision of a hand pad containing a sheet of highly ductile material and an inelastic covering therefor so that the covering is adapted to afford the maximum protection to said sheet.

30 Other objects and advantages of the invention will be apparent as it is better understood from the following description when considered in connection with the accompanying drawing illustrating a preferred embodiment thereof.

On the drawing,

45 Fig. 1 is a partial side elevation of an automobile provided with a hand pad embodying my present invention;

Fig. 2 is an enlarged section through the hand pad and door;

50 Fig. 3 is a similar section showing the hand pad before being applied; and

Fig. 4 is an enlarged perspective view of the hand pad separated from the door.

For the purpose of illustrating my present invention I have shown on the drawing

a part of an automobile disclosing a door 10 on which a hand pad 11 embodying my present invention is positioned. This hand pad is shown in detail in Figs. 2, 3 and 4, from which it will be noted, that the hand pad consists of an internal sheet 12 of highly ductile material of some suitable metal foil as lead, tin, copper or alloys of these and other metals. The inner sheet 12 is covered with an inelastic covering, leather being used 60 in the present instance. This leather covering consists of an outer, preferably grained, sheet 13 and a back sheet 14, preferably not grained. The sheets 13 and 14 are sewed together about the edges as indicated at 15. 70

The section of the car door shown on the drawing discloses the usual upholstery 16 on the combined wood and metal body 17. The binding strip 18 of the upholstery extends over the adjacent top edge 19 of the 75 pad, securing means 20 being disposed through the two and into the door body to hold the hand pad in position.

Because of the nature of the sheet, the entire hand pad readily conforms under pressure of the hand to the shape of the door both vertically and horizontally lying smooth against its outer surface. The hand pad resembles in appearance the ordinary leather pad but unlike it does not possess the tendency to turn up at the corners from continued moisture and use. Furthermore, a hand pad embodying this invention may be readily lifted back from the door and stand out of the way to permit cleaning of the outer 80 metal surface ordinarily disposed under the hand pad. If the car is to be redecorated it is not necessary to remove the hand pad as a similar lifting of it will result in the ductile material holding the pad out of contact with 85 the freshly painted car.

It is thought that the invention and many of its attendant advantages will be understood from the foregoing description, and it will be apparent that various changes may 100 be made in the form, construction and arrangement of the parts without departing from the spirit and scope of the invention or sacrificing all of its material advantages, the form hereinbefore described being merely a 105 preferred embodiment thereof.

I claim:

1. A hand pad for automobile doors and the like, comprising a sheet of highly ductile material and adapted to conform under the 110

pressure of the hand to the shape of a door on which it is positioned, said sheet being covered with an inelastic casing.

2. A hand pad for automobile doors and the like, comprising a leather casing and a sheet of highly ductile material incased therein, said sheet being adapted to conform under pressure of the hand to the door or other support against which it is positioned and will also cause the casing covering it to similarly conform.

3. A hand pad for automobile doors and the like, comprising a sheet of highly ductile material adapted to conform under pressure of the hand to the shape of the door to which it is secured, and a leather outer covering therefor.

4. A hand pad for automobile doors and the like, comprising a sheet of highly ductile material and adapted to conform under 20 the pressure of the hand to the shape of a door on which it is positioned.

5. A hand pad for automobile doors and the like, comprising a sheet of highly ductile material and adapted to conform under 25 the pressure of the hand to the shape of a door on which it is positioned, said sheet being covered with a casing.

Signed in the presence of two subscribing witnesses.

FRANK H. STANWOOD.
